UNITED STATES PATENT OFFICE.

CHARLES GILLESPIE, OF NEW BRAUNFELS, TEXAS.

RAILWAY SIGNAL.

Application filed November 18, 1922. Serial No. 601,875.

To all whom it may concern:

Be it known that CHARLES GILLESPIE, a citizen of the United States, and resident of New Braunfels, county of Comal, and 5 State of Texas (whose post-office address is New Braunfels, Comal County, Texas), has invented certain new and useful Improvements in Railway Signals, of which the following is a specification.

10 The primary purpose of the invention is to provide novel and efficient means for announcing the approach of a train to travelers on a road or street intersecting the track over which the train is passing.

15 Another purpose of the invention is to provide an improved type of signal together with means, actuatable by a passing train, for automatically shifting the signal to an operative position.

20 A still further purpose of the invention is to provide a signal which is normally disposed in an inoperative position in the street or roadway below the surface thereof, and is adapted to be raised to an operative and 25 visible position above the street or roadway by suitable mechanism arranged to be controlled by a passing train.

Other purposes and advantages of the invention as well as the novel details of construction, combination and arrangement of parts constituting the preferred embodiment disclosed herein will be more readily understood from the following description and accompanying drawings.

30 In the drawings,

Figure 1 is a plan or diagrammatical view of a railway crossing, showing the application of my invention.

Figure 2 is a fragmentary vertical sectional view through the signal device as it will appear when positioned in the roadway.

Figure 3 is a top plan view of the signal device with the cover and signal panel removed to show the interior construction.

45 Figure 4 is a front view of the signal panel and its supporting shaft.

Figure 5 is a view similar to Figure 1 but showing a modification of the invention.

Figure 6 is a vertical sectional view 50 through one of the track rails and attached compressors.

Briefly stated the invention contemplates the positioning of a signal in the roadway on each side of the intersecting track. Each 55 signal preferably comprises a box or casing which is embedded in the roadway with the

top of the box disposed flush with or below the surface of the roadway. A portion of the top of the box is formed by a pivotally mounted panel normally disposed in a horizontal and inoperative position, but adapted to be raised to an upright and operative position through the instrumentality of suitable mechanism, the operation of which is automatically controlled by a passing train. 60 Preferably the pivoted panel is actuated by a fluid motor receiving its fluid supply from one or more compressors which may be operated by the wheels of the passing train or by means of a motor included in a normally open circuit, the closing of which is effected through the wheels of the approaching train. 65

Referring more particularly to the drawings, 5 and 6 designate the signals which 70 are placed in the roadway A. on opposite sides of the track B.

As shown to advantage in Figures 2 and 3 each signal comprises a casing 7 which is embedded in the roadway with the top or cover portion of the casing substantially level with the surface of the roadway. Preferably, the top of the casing is formed in two parts comprising a stationary part 8 and a movable part 8', the latter being 75 adapted to function as a signal panel and being provided on one side with the word "Stop". The part or panel 8' is fixed to a shaft 9 through the medium of suitable brackets 10 and set screws 11, the ends of 80 said shaft being rotatably mounted in suitable bearings carried by the side walls of 85 the casing 7.

At a point intermediate its length the 90 shaft 9 is provided with spaced crank arms 12 which are pivotally secured at their free ends to a plunger rod 13 by means of an 95 elongated pin 14. The plunger rod 13 is carried by a piston 15 operating in a cylinder 16 which is pivotally mounted in the 100 casing through the medium of laterally projecting lugs 17 carried by the cylinder and 105 pivot members 18 extending inwardly through the sides of the casing 7 and received in suitable recesses or sockets provided in the ends of said lugs.

Near its opposite ends the pin 14 carries suitable eye bolts 19 to which are anchored one terminal of a pair of coil springs 20, the remaining terminals of said springs being 110 anchored to eye bolts 21 carried by the lug 17.

The cylinders 16 of the two signals are provided with air inlets 22 which are coupled together through the medium of hose connections 23 and a rigid pipe or conduit 24. The hose connections 23 are connected between the inlets 22 and the opposite ends of the conduit 24 so as to permit the cylinders 15 to have a slightly pivotal movement without disrupting the air connection.

As shown to advantage in Figure 1, the intermediate portion of pipe 24 is connected by oppositely extending pipes 25 with a plurality of air compressors 26 positioned adjacent one rail of the track B and at each side of the roadway A.

Each compressor 26 comprises a body or casing 28 having a suitable valve controlled inlet 29 and an outlet 30, the latter being connected directly to the pipe 25. The piston 31 of the compressor is provided with a stem 32 extending upwardly through a suitable gland nut or packing at the top of the casing and terminating in an enlarged head 33 which is disposed close to one rail of the track and projects slightly above the tread of the rail so as to be engaged and depressed by the flange of a wheel passing over the latter. This head 33 is normally maintained in elevated position by means of a suitable spring 34 confined therebetween and the top of the casing 28.

In order to avoid rupture of the cylinder in the event that the stroke imparted to the piston 31 should, for any reason be excessive, I provide the cylinder with a false bottom 35, resiliently supported on a suitable coil spring 36 so that the bottom of the cylinder is yieldable to the pressure of the piston when in contact therewith.

In the operation of the signal mechanism the wheels of a train approaching the roadway A from either direction will engage and operate the heads of the compressors on that side of the road corresponding to the direction from which the train is approaching. Air is thus supplied through the pipes 25 and 24 to the cylinders 16 thus moving the pistons 15 toward the free ends of the cylinders for swinging the signal panels 8' to an upright and operative position above the surface of the roadway A, so as to serve as a warning to traffic passing in both directions toward the railway track.

It will be understood, of course, that suitable check valves may be provided at the intersection of the pipes 24 and 25 so as to prevent the air delivered by one set of compressors from passing to the compressors of the opposite set.

After the train has passed, the compressed air is exhausted from the cylinder 16 through the medium of a small exhaust opening 37 and if the action of gravity is not sufficient to return the pistons and panels

8' to normal position, this will be accomplished by the springs 20 which have been placed under tension by the movement of the panels to operative position.

In the modifications shown in Figure 5, the pipe 24 is connected by a pipe 24' to a single compressor 38, the shaft of which is directly coupled to the shaft of an electric motor 39. One terminal of the motor 39 is connected to a line wire 40 while the remaining terminal thereof is connected to the contact 41 of a magnetic switch 42, a further contact 43 of said switch is connected directly to the remaining line wire 44 and the latter is connected by a tap wire 45 to one rail of the track B. The remaining rail of the track is connected by a wire 46 to a terminal 47 of the relay 42. 48 indicates a further wire connected between the line wire 40 and a terminal 49 of the said relay.

The sections of the rails to which the wires 45 and 46 are connected are insulated from the remaining rail sections as indicated at 50, the length of the insulated sections being approximately 1,000 feet. When the track circuit is closed by a passing train relay 42 will be energized to close contacts 43-41 which closes the motor circuit permitting the current to pass through the wire 44 to the terminal 43 of the movable part of the relay, and from the terminal 44 to one terminal of the motor 39 from whence it passes from the remaining terminal of the motor to the line wire 40.

As magnetic relays of the type above referred to are well known it is thought that the description given is sufficient for the purposes of this invention as the only essential requisite is that the relay shall act to close a motor circuit excluding the rails of the track and the metal work of the train which are initially utilized to close the circuit including the magnetic part of the relay so as to attract thereto the movable part carrying the terminals of the motor circuit.

Having thus fully described my invention, it will be understood that I do not limit myself to the exact details of construction, combination and arrangement of parts herein disclosed, but reserve the right to resort to such modifications as may be found desirable, providing, of course, that the same do not depart from the spirit and scope of the appended claims.

What I claim is:

1. A signal of the character described, comprising a casing, a signal panel normally closing the top of the casing, a shaft extending across the casing and supporting said panel for swinging movement in a vertical direction, and means contained within the casing for operating said shaft comprising a cylinder, a piston operating in the cylinder and connected with said shaft, means for supplying fluid to the cylinder

to move the piston in one direction and spring means connected between the cylinder and the piston for moving the latter in the opposite direction.

5. 2. A signal of the character described comprising a casing, a shaft journalled to extend transversely thereof, a signal panel fixed to said shaft and normally disposed in horizontal position, a crank arm fixed to said shaft, a cylinder having a piston operating therein, a piston rod having one end connected to said piston, a transverse pin coupling the remaining end of the piston rod to the aforesaid crank arm, pivot means 10 supporting said cylinder for swinging movement and spring means connected between said pivot means and said pin and serving to resist movement of the piston in one direction and means for supplying fluid to the cylinder to move the piston against the resistance of said spring.

15 3. A signal of the character described comprising a casing having an opening in

its top wall, a normally horizontal signal panel closing said opening, a shaft journalled in the sides of the casing and extended beneath the panel adjacent one longitudinal edge thereof, means securing the panel to said shaft so as to move therewith, a crank arm fixed to said shaft, a cylinder 20 contained within said casing, pivot means supporting said cylinder at one end to permit vertical swinging movement thereof, a piston operating in said cylinder, a piston rod fixed at one end to said piston, a pin 25 coupling the other end of the piston rod to the free end of the aforesaid crank arm, means for supplying fluid to the cylinder to move the piston in one direction and spring means arranged to resist the aforesaid movement of the piston and to return the latter to normal position subsequent to such movement.

30 In testimony whereof I hereunto affix my signature.

CHARLES GILLESPIE.
